SHOE HOLDING DEVICE

Roger H. David, St. Paul, Minn.

Application June 10, 1948, Serial No. 32,195

4 Claims. (Cl. 12—128)

1

My invention relates to an improvement in shoe holding device wherein it is desired to provide a means of supporting a shoe during a shoe fitting operation.

The object of the present invention lies in the provision of a simple and efficient device for supporting a shoe during a shoe shining operation. The device is supported upon a wall or similar support during operation and may be removed from position for storage while not in use.

A feature of the present invention lies in the provision of a simple device capable of supporting a shoe and which is adjustable to accommodate shoes of varying sizes. A toe portion is designed to extend into the toe of the shoe and this portion is provided with a removable cap for accommodating shoes of larger size.

A feature of the present invention lies in the provision of a shoe support equipped with a slideable element engageable within the rear portion of the shoe above the heel. This portion of the device is shaped somewhat similarly to a shoe horn and engages the rear of the shoe to hold the same supported.

A feature of the present invention resides in the provision of a slide supporting the slideable element which may be easily manipulated. The slide is provided with an upwardly projecting flange by means of which the slide may be actuated. This flange projects above the upper surface of the supporting arm, providing ready accessibility to the flange for adjusting the slide.

A further feature of the invention lies in the fact that the toe portion is integral with the supporting arm. This structure is simple and inexpensive, and yet stronger than constructions involving several parts secured together.

These and other objects and novel features of my invention will be more clearly and fully set forth in the following specification and claims.

In the drawings forming a part of my specification:

Figure 1 is a perspective view of my shoe holding apparatus showing the construction thereof.

Figure 2 is a longitudinal section through the structure shown in Figure 1.

Figure 3 is a sectional view through the device, the position of the section being indicated by the line 3—3 of Figure 2.

Figure 4 is a sectional view through the toe portion of the device, the position of the section being indicated by the line 4—4 of Figure 2.

Figure 5 is a plan view of the wall bracket for supporting the device.

2

The shoe holding device is mounted upon a wall bracket best illustrated in Figures 1, 2, and 5 of the drawings. This device comprises a plate 10 having side flanges 11 and 12 thereon. Portions of the plate are recessed to accommodate screws or similar fastening means. Two such recessed portions 13 are provided near the upper end of the plate 10 while a third recessed portion 14 is provided centrally of the plate near the lower end thereof. Apertures are provided through these recessed portions for accommodation of screws or similar means for holding the plate 10 to a wall or similar support.

The front surface of the plate is provided with two sets of hook shaped elements. The uppermost set of elements are indicated by the numerals 15 and comprises two opposed hook shaped flanges bent from the body of the plate 10. A similar pair of elements 16 are provided near the lower end of the plate 10. These hook shaped elements are designed to slidably engage the shoe holder as best illustrated in Figure 1 of the drawings.

The shoe holding device includes a supporting plate 17 having co-planar side flanges 19 which extend over the surface of the plate 10 and engage beneath the hook shaped elements 15 and 16. These flanges 19 form a part of the depending arm 20 at one end of the shoe holding device, this arm being equipped with a central rib 18 for strengthening purposes. At its upper extremity the arm 20 extends laterally as indicated at 21 to form a support for the slideable heel engaging element 22 which will be later described in detail.

The forwardly extending arm portion 21 merges into a downwardly and forwardly inclined portion 23 which terminates in an enlarged tapered toe portion 24. The arm portions 21 and 23 as well as the toe portion 24 is trough shaped or channel shaped in section for maximum strength. The forward end of the toe portion 24 bends downwardly as indicated at 25.

A slot 26 is provided in the horizontally extending arm portion 21. The heel engaging portion 22 is trough shaped or channel shaped in section and is provided with a forwardly rounded lower end 27. At its upper extremity the member 22 is provided with a horizontally extending portion 29 which fits beneath the arm portion 21. An upwardly directed end flange 30 on the portion 29 extends through the slot 26.

A plate 31 rests upon the upper surface of the arm portion 21 on opposite sides of the slot 26. A center depressed portion 32 extends into

3
the slot 26 into contact with the upper surface of the slide portion 29. The flange 30 extends through an aperture 33 at the end of the depressed portion 32 so as to hold the slide element 22 in proper relation to the slot 26. A rivet or other suitable means 34 connects the plate 31 to the slide portion 29. An upwardly extending flange 35 on the rear edge of the plate 31 permits this plate and the slide element 22 connected thereto to be manipulated forwardly or rearwardly.

10 A removable toe portion 36 is provided to overlie the toe portion 24 when the device is to be used in shoes of larger sizes. The removable toe portion 36 is trough shaped in section and is somewhat wider than the toe portion 24. An indentation 37 is provided in the upper portion of the toe member 36 and is engageable in an aperture 39 in the toe portion 24. A flat thumb nut 40 is pivotally attached at 41 to a depressed portion 42 of the toe member 36. This thumb nut 40 engages through an elongated slot 43 in the toe portion 24 and may be turned at right angles as illustrated in Figures 2 and 4 of the drawings to hold the toe member 36 in place. The engagement of the thumb nut 40 through the aperture 43 and the engagement of the indentation 37 in the aperture 39 holds the toe member 36 longitudinally aligned on the forward end of the arm 23.

15 The operation of my device will be understood from the foregoing description. When it is desired to use the device for supporting a shoe, the depending end 20 is engaged in the bracket 10 so that the forwardly projecting arm portion 21 extends outwardly at substantially right angles to the supporting wall. If a large shoe is to be supported the toe member 36 is applied to the bottom end of the arm. The toe portion of the arm is inserted into the toe of the shoe. The heel engaging element 22 is slid forwardly and the shoe is elevated so that this heel engaging portion is within the shoe. The element 22 is next moved rearwardly until the heel engaging portion engages within the rear end of the shoe. This action tends to twist the heel engaging element 22, causing it to bind against the laterally extending arm portion 21. The shoe is removed from place by a reversal of this process.

20 In accordance with the patent statutes, I have described the principles of construction and operation of my shoe holding device, and while I have endeavored to set forth the best embodiment thereof, I desire to have it understood that obvious changes may be made within the scope of the

following claims without departing from the spirit of my invention.

I claim:

5 1. A shoe holding device comprising an arm having an anchoring end, a forwardly extending horizontal portion connected to said end, a forwardly and downwardly inclined arm portion on said horizontal portion, and a toe portion on the end of said forwardly and downwardly inclined portion, said forwardly extending portion having an elongated slot therein, a heel engaging element, said heel engaging element engaging the undersurface of said horizontally extending portion on opposite sides of said slot, a plate on said heel engaging element overlying said horizontally extending portion and connected to the remainder of said heel engaging element through said slot, and means for holding said plate in proper alignment with said slot including an upwardly directed tongue on the portion of the heel engaging element beneath said horizontal arm portion, said plate having an aperture therethrough through which said tongue is engaged.

10 2. The structure defined in claim 1 and including an upwardly directed flange on said plate.

15 3. The structure defined in claim 1 and including a depressed portion on said plate engaged in said slot.

20 4. The structure defined in claim 1 including a toe cap element, an elongated slot in the toe portion on said arm, and a pivotal thumb nut on said toe cap portion engageable through said slot.

25 ROGER H. DAVID.
